UNITED STATES PATENT OFFICE.

DEXTER C. BAKER, OF OAKLAND, CALIFORNIA, ASSIGNOR TO BAKER-HANSEN MANUFACTURING COMPANY, OF OAKLAND, CALIFORNIA.

COMPRESSOR.

Application filed October 26, 1920. Serial No. 419,714.

To all whom it may concern:

Be it known that I, DEXTER C. BAKER, a citizen of the United States, and resident of Oakland, county of Alameda, State of California, have invented a new and useful Compressor, of which the following is a specification.

The present invention, while relating in general to the art of air and gas pumps, has reference more particularly to an improvement in air compressors for creating a suitable source of compressed air such, for instance, as is used in air brake systems and in other capacities where it is necessary to realize upon a store of compressed air source.

In so far as concerns the preferred embodiment of the invention, it is proposed to provide a single unit compressor, including a pair of rectilinear single-acting pistons, both of which being driven by an eccentric drive. With this construction in view, and by means of the novel valve arrangement for controlling the effective port area of the intakes and outlets for introducing the air to be acted upon by the pistons and subsequently stored or, rather, delivered to the storage tank or other like container, it is possible to realize an exceedingly practical solution of the problems involved in an apparatus of this character.

That form of the invention which has been selected for the purpose of illustration is shown on the accompanying drawings, in which Figure 1 is a plan view of the compressor; Figure 2 is a view in elevation of one of the end plates; Figure 3 is a view in elevation of the opposite end plate; Figures 4 to 7 inclusive are side elevations of the valve arrangement for both ends of the compressor; Figure 8 is a view in cross-section through the middle of the compressor and showing the journal bearing for the drive shaft; Figure 9 is a side view of the drive shaft, including the pitman, and showing the anti-friction bearings in longitudinal section; Figure 10 is an end view of the drive shaft, including the pitman, and showing the anti-friction bearing for the pitman in elevation, and Figure 11 is a horizontal section through the compressor as assembled, and showing the co-operative relationship of the parts.

Referring now to the drawings in detail, attention is invited to Figures 1 and 11, from which it will be noted that one of the

salient features of the invention resides in the relatively small dimensions of the assembled construction. This desirable feature is realized by the construction and operative association of the parts without sacrificing the capacity of the compressor for creating the desired air pressure; in other words, while it is obvious that the compressor may be made in different sizes to accommodate the same to different uses, without departing from the spirit of the invention, the peculiar construction and practical arrangement of the parts will enable the compressor to function with a greater efficiency than those compressors heretofore employed.

According to the present illustration, the compressor includes a pair of cylinders of different stages, each of which having a piston corresponding in size to its respective cylinder. This should not be considered as a limitation, as in some cases it may be desirable to arrange the cylinders and the pistons therefor in more or less equal size and capacity.

As will be seen, it is preferred to employ a pair of opposed co-axial cylinders (1) and (2), each of which for cooling purposes being provided with the customary fins or the like (3) and joined end to end by a middle section or crank case (4), the same having a greater diameter at one end than the other to accommodate it to the small and large cylinders (1) and (2) respectively.

As a convenient means of assembling the cylinders and the section (4) rods (5) may be carried by the section (4) with openings in the fins (3) of each of the cylinders through which the rods are passed and with the rods terminating in threads made to receive the nuts (6).

The ends or heads of each of the cylinders (1) and (2) are closed by suitable plates (7) and (8) which are provided with openings through which the rods (5) pass with the nuts (6) arranged on the outer faces of the plates. These plates also include air ports, which will be presently described.

As will be seen more clearly from Figures 1 and 8, the middle section or crank case (4) includes a transverse journal bearing (9) which enters the crank case from the side thereof to provide a bearing for the drive shaft (10) which also has associated with it the anti-friction bearing (11) which

is of a diameter substantially that of the journal bearing (9) so as to provide a tight fit. Arranged on the outer end of the journal bearing (9) is a sleeve or collar 5 (12) which has an axial bore of substantially the diameter of the shaft (10) so as to restrict the opening of the journal bearing (9) to a size of that of the shaft and thus close the end of the same. A suitable 10 standard or the like (13) is employed to encircle the journal bearing (9), with its opposite end providing a support.

The drive shaft (10) terminates on its inner end in a so-called crank which primarily 15 comprises a block (14) which is eccentrically mounted upon the end of the shaft and with a short crank pin (15) eccentrically mounted upon the face of the block (14) and extending outwardly therefrom parallel to the shaft (10). Carried by the short crank shaft (15) is the anti-friction device (16). The crank is adapted to be introduced into the crank case (4) and assume a position substantially intersecting 20 the axis of the cylinders (1) and (2).

As previously mentioned, each one of the cylinders is adapted to house its respective piston, said pistons being arranged in rectilinear alignment and represented as at (17) 25 and (18). The piston (17), which is constructed to accommodate it to the larger one of the cylinders, is preferably hollow to reduce its weight owing to its larger diameter than the piston (18), but the same will also 30 include a relatively large axial and rearwardly extending part (19) which terminates substantially in alignment with the inner periphery of the pistons to provide a radial shoulder bearing (20). This does not 35 mean that the part (19) is abruptly cut off to provide the shoulder (20) as in reality, and as best shown in Figure 8, the reduced thickness of the member provides a continuation (21) to connect the piston (18) 40 to make both of the pistons practically one and the same piece. The continuation (21) will be presented at right angles to the axis of the shaft (10) so as to enable the pitman to be introduced and confined between the 45 radial shoulder (20) on the piston (17) and a like radial shoulder (22) on the piston (18). The surfaces of the shoulder (20) and the shoulder (22) are parallel to one another and the space between them is of sub- 50 stantially the same dimension as the diameter of the ball-bearing anti-friction device (16) of the pitman. Owing to the small diameter of the piston (18) it will not be necessary to hollow the same out as in the case of the 55 piston (17). For this reason it may be 60 solid.

Both of the pistons will be equipped with rings (23) and (24).

With the pitman confined between the 65 shoulders (20) and (22) of the pistons, and

by imparting a suitable rotary drive to the shaft (10), the eccentric of the pitman will convert the rotary movement of the shaft into a reciprocating motion of the pistons. The dotted lines in Figure 11 will indicate 70 the action of the pitman.

With reference now to the admittance or introduction of air from the atmosphere into the working cylinders where it will be acted upon by the pistons and delivered to a point 75 where it may be stored, attention is directed to the valves and ports associated with the end plates or heads (7) and (8). In the present showing, the piston (17) may be said to introduce or suck the air into the 80 compressor, whereas the piston (18) is a secondary compressing medium in that, while it does not introduce the air from the atmosphere into its respective cylinder, it acts upon the air which has been transferred from the cylinder (2) by the piston (17) into the cylinder (1); therefore, the primary intake is located in the plate or head (8) and may be represented by the plurality of ports (25) which are arranged 85 in spaced relation around the head and communicate directly with the compression chamber of the cylinder (2) in front of the piston (17). The valve or means for opening these intakes upon the suction stroke of the piston (17) and closing them upon the compression stroke of the same, comprises a relatively thin flexible disc (26) which is of such diameter that when centered on the inner face of the head (8) the edge thereof 90 will overlap the openings (25). Considering the disc (26) as being maintained flat against the inner face of the head by the centering and holding bolt (27) and particularly as the inner face of the head is 95 slightly concave and, furthermore, by using a pair of auxiliary discs (28) and (29) to overlay the inner dimensions of the disc (26), the outer periphery or edge of the disc (26) is more or less flexible, with its 100 central part maintained rigid and flat against the concave of the head as mentioned. With this construction contemplated, a suction stroke of the piston (17) 105 will operate to flex the edge of the disc (26) and move it slightly from its sealing position to the openings (25) which will establish the desired intake. On the compression stroke of the piston the edge of the disc (26) will naturally be forced to close 110 the openings (25) which will trap the air in the cylinder as far as concerns an outlet through the intake openings.

Arranged inwardly of the openings (25) and spaced apart, are a plurality of openings (30) which effect a communication between the compression chamber of the cylinder (2) and a distributing chamber (31) which is formed by the housing (32). These openings 115 are normally unobstructed so far as 120

concerns the passage of air from the compression chamber of the cylinder to the distributing chamber (31); at least the discs (26) and (28) are perforated as at (33) and the perforations (33) never change their position with reference to the openings (30) to the extent that the openings (30) will be obstructed. At the same time, a second set of disc valves are employed within the distributing chamber (31) to seal the openings (30) against back pressure from the distributing chamber (31) to the compression chamber of the cylinder (2). One of these discs, i. e., (34) is of a diameter sufficient to overlap the openings (30) when the same is centered upon the bolt (27). The face of the head (8) within the distributing chamber (31) is slightly concave and an auxiliary disc (35) is caused to overlay the inner dimension of the disc (34) to add rigidity to the same, at the same time permitting its outer edge to flex so that when upon the compression stroke of the piston (17) the air previously admitted, by the suction stroke, into the compression chamber will be forced through the openings (33) in the discs through the openings (30), the pressure thereof causing the edge of the disc (34) to flex and permit the air to be forced into the distributing chamber (31). Upon the suction stroke of the piston (17) the edge of the disc (34) will be caused by the suction to overlap the openings (30) and seal the same in so far as concerns the distributing chamber (31).

From the above it will be seen that these discs are in many respects flexible diaphragms and that they are used in the capacity of valves. Of course it should be understood that the showing made in Figure 11 does not represent the true active position of the discs one to the other, nor to the head (8), as in this figure they are shown spaced apart to distinguish the same one from the other. They may be readily clamped into proper position by screwing up on the nut (36) of the bolt (27).

Particular notice should be given the annular grooves (25^a) arranged on the inside of the openings (25) and the annular grooves (30^a) and (30^b) which are arranged on the inner and outer sides respectively of the openings (30). This construction in fact is really an annular continuation of the openings (25) around the inside of the plate or head (8) and an annular continuation of the openings (30) on both the inside and outside of the plate or head (8).

When the air after being sucked into the compression chamber of the cylinder (2) has been transferred into the distributing chamber (31) of the housing (32) by a compression stroke of the piston (17), it is transferred to and acted upon by the piston

(18), and to realize this transfer a connection (37) is arranged in the housing (32) with a tubing or the like (38) fixed to the connection (37) and extending in any suitable manner around the compressor and 70 communicating with the connection (39) which is arranged in the housing (40) which is connected to the head or plate (7) of the cylinder (1).

The plate or head (7) includes a slightly 75 modified construction from that of the plate or head (8) in that it comprises an annular outer groove (41) which is adapted to communicate with a hollowed out portion (42) of the housing (40) so that the air transferred through the tubing (38) may be introduced into this annular groove (41). Arranged in the thickness of the plate and at an angle to the annular groove (41) are a plurality of openings or ducts (43) which 80 terminate inwardly in the comparatively narrow annular groove (44); consequently the ducts (43) establish a communication between the tubing (38) and the compression chamber of the cylinder (1) in very 85 much the same manner as the openings (25) establish a communication from the atmosphere in to the compression chamber of the cylinder (2). The annular groove (44) acts in the same capacity as the annular groove 90 (25^a) at the other end of the compressor. As a means for overlapping and closing the ducts (43) a disc (45) is centered upon the bolt (46) with its edge overlapping the groove (44) and with a secondary disc (47) 95 co-axially placed upon the bolt (46) to maintain the disc (45) rigid against the slightly concave inner face of the plate (7) so that the air in being forced through the tubing (38) may occupy the compression 100 chamber of the cylinder (1) by flexing the edge of the disc (45) at a point where it overlaps the groove (44). It is to be noted that when the piston (17) is on a compression stroke which would act to force air 105 through the tubing (38), the piston (18) is on a suction stroke; therefore, the air is not only forced through the tubing (38) but it is also sucked therethrough, or looking at the function in a different light, it 110 may be said that the piston (18) in effect produces a vacuum on its suction stroke which will enable the air to be readily introduced into the cylinder.

Arranged in the plate or head (7) inwardly of the ducts (43) are a plurality of openings (48) which are really a duplication of the openings (30) in that annular grooves (48^a) and (48^b) are arranged on opposite sides of the plate (7) and the openings establish a communication between the compression chamber in front of the piston (18) into the chamber (49) of the housing (40). This communication is always open from the inside of the compression chamber by means 130

of an opening (50) arranged in the disc (45) in front of each of the openings (48).

Carried upon the centering bolt (46) within the chamber (49) is a disc (51) which is of a dimension sufficient to overlap the groove (48^a) and adapted to bear against the concave outer face of the plate. This disc in overlapping the groove (48^a) provides a valve closure for the opening (48) from the chamber (49) into the compression chamber of the cylinder, but upon a compression stroke of the piston (18) the edge of this disc is flexed to permit the piston to transfer the air from the compression chamber into the chamber (49). Overlapping this disc (51) is an auxiliary disc (52) which is likewise centered upon the bolt (46) to add rigidity to the center dimension of the disc as in the case of the other discs.

20 The position of the discs (45), (47), (51) and (52) is abnormal in that they are shown spaced apart to distinguish them one from the other. They may be clamped in the proper active position by screwing up on the nut (53) as explained with reference to the opposite end of the compressor.

Communicating with the chamber (49) is a connection comprising a check valve (54) which is adapted to connect with a piping 30 or tubing for delivering the compressed air created by the compressor into a suitable storage.

Arranged in the base of the crank case (4) is an oil basin (55). (See Figure 8). 35 The top of the crank case is equipped with breather openings (56).

I claim:

1. In an air compressor, a pair of co-axially arranged cylinders, a pair of rectilinear 40 pistons in said cylinders, said pistons being

made as a unitary structure with a connecting web eccentrically positioned relative to the axis of the pistons, and a drive for said pistons comprising an eccentrically mounted rolling crank presented between the parallel 45 inner ends of the pistons transversely of the axis thereof and opposite the said connecting web, one of said pistons having a larger diameter than the other with the said cylinders made correspondingly, the smaller one 50 of said pistons comprising a solid structure and the larger one being a hollow with an axial annular solid block-like structure within its hollow, the diameter of said block-like structure being equal to that of the 55 diameter of the smaller solid piston and arranged co-axially thereof.

2. In an air compressor, a pair of co-axially arranged cylinders, a pair of rectilinear pistons in said cylinders, said pistons being 60 made as a unitary structure with a connecting web eccentrically positioned relative to the axis of the pistons, and a drive for said pistons comprising an eccentrically mounted rolling crank presented between the parallel 65 inner ends of the pistons transversely of the axis thereof and opposite the said connecting web, said cylinders being made as separate units with a separate crank case connecting the same end to end, one of said pistons having a larger diameter than the other with the said cylinders made correspondingly, the smaller one of said pistons comprising a solid structure and the larger one 70 having a hollow with an axial annular solid 75 block-like structure within its hollow, the diameter of said block-like structure being equal to that of the diameter of the smaller solid piston and arranged co-axially thereof.

DEXTER C. BAKER.
